UNITED STATES PATENT OFFICE.

ELMER RICHARD BOUCHARD, OF KNOWLES, OKLAHOMA, ASSIGNOR OF ONE-HALF TO
GUY PARKER, OF KNOWLES, OKLAHOMA.

PITMAN.

1,225,756.

Specification of Letters Patent. Patented May 15, 1917.

Application filed October 9, 1916. Serial No. 124,571.

To all whom it may concern:

Be it known that I, ELMER R. BOUCHARD, a citizen of the United States, residing at Knowles, in the county of Beaver and State 5 of Oklahoma, have invented a new and useful Pitman, of which the following is a specification.

This invention has reference to pitmen, and its object is to provide a pitman, which 10 will automatically compensate for wear.

The invention is particularly applicable in connection with wheat and Kafir corn harvesters.

Difficulty is experienced in properly lubricating and adjusting the pitmen where engaging wrist pins and oftentimes the pitmen will run dry and wear, or the harvester must be stopped at frequent intervals for lubrication. To overcome these difficulties, 15 the present invention provides a composite structure consisting of a suitable casing constituting the body of the pitman with journal blocks for encircling the wrist pins, means for oiling and supplying grease to 20 the bearings and constantly active means for maintaining the bearings permanently 25 tight by taking up all wear.

The invention will be best understood from a consideration of the following detailed description, taken in connection with the accompanying drawings forming part 30 of this specification with the further understanding that while the drawings show a practical form of the invention, the latter 35 is not confined to strict conformity with the showing of the drawings, but may be changed and modified so long as such changes and modifications come within the scope of the appended claims.

40 In the drawings:—

Figure 1 is a side elevation of a pitman constructed in accordance with the present invention, the wrist pins being shown in cross section.

45 Fig. 2 is a top plan view of the pitman, shown in Fig. 1.

Fig. 3 is a longitudinal central section with some parts shown in elevation.

50 Fig. 4 is a section on the line 4—4 of Fig. 1.

Fig. 5 is a section on the line 5—5 of Fig. 2.

55 Referring to the drawings, there is shown a casing 1, which may consist of a strip of sheet steel bent or pressed into elongated

U-shape, with the free ends of the legs of the U bent toward each other to provide overlapping extremities 2, 3 respectively, which may be finally united by rivets 4, or in any other suitable way to thereby provide an elongated closed rectangular frame, 60 which at the ends has widened portions 6 designed to be traversed by wrist pins 7, 8 on the parts to be connected by the pitman.

The leg portions of the frame have longitudinally extended side flanges 9 bent one toward the other and at the ends cut away from the top and bottom members of the frame to provide elastic tongues 10 for a purpose to be described. The end portions 70 of the frame have also bent-over flanges 11 directed toward the central portion of the frame. This provides a frame with side flanges leaving open spaces between them less than the thickness of the frame 75 from top to bottom, it being assumed that the pitman in the installed position is in an approximately horizontal position and expressions of location with respect to the pitman have reference to such installed position. Lodged in each widened end 6 of the pitman are bearing blocks 12, 13, respectively, grooved out, as shown at 14 to receive the respective wrist pin 7 or 8, as the case may be. These blocks are so arranged 80 that when first applied, they are spaced apart at their meeting ends, such spacing being indicated at 15, so that as the grooves 14 forming seats in the blocks for the respective wrist pin wear, such wear 85 may be at once taken up by the approach of the blocks one toward the other. The blocks are held snugly in place against escape from the frame 1 by the top and bottom members of the frame, the flanges 9 90 so far as they engage the blocks, the elastic tongues 10 and the end flanges 11 together with other flanges to be described.

The blocks 12 and 13 are of about or somewhat less than the length of the widened 100 end 6 containing them. The mid portion of the frame 1 between the ends 6 contains other blocks 16, 17 bearing against the respective blocks 13 through cushion pieces 18 of leather or other suitable material whereby a slightly yieldable contact 105 between the respective blocks is provided. This is of advantage since while it is customary to make bearing blocks of metal the blocks 13 are made of wood.

The blocks 16 and 17 are also made of wood, thus correspondingly lightening the pitman. Each block 16 and 17 is traversed by an elongated slot 19 extending from the top plate to the bottom plate of the frame 1. Each slot 19 is traversed by the shank of a bolt 20 having a squared portion 21 extending through the bottom plate and terminating in a head 22 bearing against the under face of the bottom plate. The other end of the shank of the bolt extends through the top plate and terminates in a threaded portion 23 to which is applied a nut 24 confining a spring 25 between the top plate of the frame 1 and a washer 26 traversed by the bolt and engaged by the nut.

The tension of the spring 25 is readily regulated by the nut 24 and the latter is held against turning by a cotter pin 27, or any other suitable pin extending through any suitable one of a number of holes 28 produced in the threaded end of the bolt and lodging in any one of a number of grooves 29 in that face of the nut remote from the washer 26. The cotter pin serves as a convenient means for locking the nut in any suitably adjusted position. The bolts 20 with the springs 25 provide a yieldable holding means for preventing separation of the long sides of the frame 1 without undue binding on the blocks 16 and 17, and at the same time holding the parts tight enough to prevent rattling under conditions of use. The meeting ends of the blocks 16 and 17 are beveled, as shown at 30, the bevel of one block being opposite to that of the other to provide a wedge-shaped passage for a pyramidal wedge head 31 on one end of a bolt shank 32, the other end of which is screw-threaded, as shown at 33, to receive a nut 34 with grooves 35 in one face to lodge a cotter pin 36 traversing the threaded end of the bolt through any one of passages 37. Surrounding the shank of the bolt 32 is a conical spring 38 bearing at the large end upon the top plate of the frame 1 and at the small end engaging a washer 39 bearing against the nut 34. Interposed between the head 31 and the beveled ends 30 of the blocks 16 and 17 are plates or sheets 40 of leather, or other suitable soft material of more or less cushioning nature. Furthermore, leather sheets 41 are set in the respective blocks 16 and 17 immediately beneath that portion of the top of the frame 1 engaged by the spring 38. The purpose of the wedge head 31 is to urge the blocks 16 and 17 toward the respective ends of the pitman thus constantly urging the blocks 13 toward the blocks 12 and maintaining the journal bearings of the respective wrist pins sufficiently tight to avoid rattling. The action of the spring 38 is to constantly draw the head 31 in between the respective blocks 16 and 17 in a direction to separate these blocks and

therefore automatically take up all wear which may occur in the blocks 12 and 13 where engaging the wrist pin. Those ends of the blocks 16 and 17 presented toward the block 13 are reduced in height providing seats for sheets or plates 42 of leather, or other suitable material and the end of each block 16 and 17 has fast thereto a plate 43 which may be of sheet metal extending beyond the sides of the block and bent over to form flanges 44 aiding in maintaining the blocks 13 within the frame 1. The plates 43 are held to the respective blocks 16 and 17 by screws 45, or in any other suitable manner.

Riveted, or otherwise secured to the top plate of the frame at about the meeting points of the blocks 13 with the respective blocks 16 and 17 are metal plates 46 of sufficient thickness to be tapped for the reception of the threaded neck 47 of a grease cup 48 of known construction, and so needing no particular description. Extending through the corresponding ends of the blocks 13 and the respective blocks 16 and 17 are passages 49 leading from grease cups 48 to the bearings for the wrist pins 7 and 8, there being a grease cup for each wrist pin. Also leading to the bearings for the respective wrist pins and opening through raised portions 50 of the top plate of the frame are passages 51 constituting oiling passages for the wrist pins.

When the machine containing the pitman is in operation, the wrist pins are preliminarily lubricated through the passages 51 and the grease cups 48 are filled in the usual manner with lubricating grease. So long as the initial lubrication is effective, the grease cups remain inert, but when the initial lubrication ceases the wrist pin bearings begin to heat, and such heat is ultimately conducted to the grease cups, thus liquefying the grease, which flows to the bearings and provides further lubrication. It will be understood that the usual pendent grease cups may be used if desired and they may be provided with the customary safety springs to prevent loosening. Such temperature action in causing lubrication is sufficiently slow to maintain lubrication without waste of lubricant, wherefore a single filling of the grease cups is sufficient for a day's work, without any danger of undue heating of the wrist pins or their bearings, and without attention on the part of the operator of the machine.

Heretofore, frequent lubrication has been necessary, or in the absence of such lubrication, damage has occurred through wear to the wrist pin bearings and the wrist pins themselves with the result that the parts soon became loose and rattled. With the present invention, the parts are always in well lubricated condition, the action being

entirely automatic and the parts are always maintained tight, whereby rattling is entirely avoided without any attention, the structure automatically taking up or compensating for all wear.

Furthermore, the pitman is of especially strong construction without liability of damage and at the same time light in weight as compared with a pitman of the same capability of resistance to damage if made in the form of a casting or forging.

It will be understood, of course, that the invention is useful on mowing machines and binders as well as headers, and may, in fact, be used in any machine to which it is adapted.

What is claimed is:—

1. A pitman comprising an open sided frame with pairs of journal blocks at the ends adjustable for wear, intermediate blocks between the pairs of journal blocks and movable lengthwise of the frame to correspondingly move the journal blocks of each pair together, spring-actuated means between the intermediate blocks and having a constant tendency to spread the blocks apart, and holding means extending through the frame and through the intermediate blocks with the latter movable in the direction of their length on the holding means, whereby the frame is held from spreading at points intermediate of its length.

2. A pitman comprising a frame with journal blocks at opposite ends, intermediate blocks between the first named journal blocks and having beveled adjacent ends and also being slotted between the ends, bolts traversing the slots and the frame and provided with springs bearing against one face of the frame, a bolt traversing the frame between the beveled ends of the intermediate blocks and provided with a wedge-shaped head engaging the beveled ends of the blocks, and a spring surrounding the last-named bolt and bearing against the face of the frame.

3. A pitman comprising an open sheet metal frame with longitudinal side flanges having flexible extremities, journal blocks

seated in the end portions of the frame and removable therefrom, other blocks in the frame intermediate of the ends of the frame and bearing against the journal blocks, and spring actuated means having a constant tendency to move the intermediate blocks against the journal blocks.

4. A pitman comprising an open sheet metal frame with longitudinal side flanges having flexible extremities, journal blocks seated in the end portions of the frame and removable therefrom, other blocks in the frame intermediate of the ends of the frame and bearing against the journal blocks, and spring actuated means having a constant tendency to move the intermediate blocks against the journal blocks, the end portions of the frame having flanges extending laterally of the length of the frame to retain corresponding journal blocks, and the intermediate blocks having flanged members engaging others of the journal blocks for holding them against lateral movement in the frame.

5. A pitman having journal blocks at opposite ends for engaging corresponding journals and provided with passages for the preliminary application of lubricant between the blocks for the respective journals to reach journals mounted therein, other blocks between the pairs of journal blocks and engaging the latter to hold the journal blocks against journals mounted therein, and lubricant cups adjacent to the journal blocks for the lubrication of the journals by grease softened by heat frictionally generated in the journal blocks, said second-named blocks and the journal blocks adjacent thereto having matching passages for conducting lubricant from the cups to the respective journals.

In testimony, that I claim the foregoing as my own, I have hereto affixed my signature in the presence of two witnesses.
